UNITED STATES PATENT OFFICE.

WILLIAM VANDERMAN, OF WILLIMANTIC, CONNECTICUT.

FIREPROOF BOX.

SPECIFICATION forming part of Letters Patent No. 773,269, dated October 25, 1904.

Application filed December 6, 1902. Serial No. 134,162. (No model.)

To all whom it may concern:

Be it known that I, WILLIAM VANDERMAN, a citizen of the United States, and a resident of Willimantic, in the county of Windham and State of Connecticut, have invented certain new and useful Improvements in Fireproof Boxes, of which the following is a specification.

My invention relates to that class of boxes more especially designed for affording protection for valuable papers or the like from injury to a greater or less extent by fire; and the object of my invention is to provide a cheap, durable, comparatively light, and effective structure for such use. A form of box in which these objects may be attained is illustrated in the accompanying drawings, in which—

Figure 1 is a perspective view in section through a box embodying my improvement. Fig. 2 is a view in section through a part of the box, showing the means of protecting the joint at the point where the cover and sides meet. Fig. 3 is a like view showing a modified form of the improvement. Fig. 4 is a detail view showing the upper edge of the front of the box. Fig. 5 is a detail view showing a sheet of the packing.

It has been found that there is a want for a box in which papers and the like may be stored and be safe to a greater or less degree from injury by fire. Safes of the ordinary pattern and structure do not fill this requirement, for the reason that they are too heavy and bulky. In order to provide the requisite structure, it has been found that a receptacle may be constructed of sheet metal which will answer all the requirements. In the drawings herein is shown a box of this nature provided with means whereby papers or the like contained in the interior may be shielded from fire to a greater or less extent.

In the form of construction of the fireproof box which embodies my invention it is necessary that all of the several parts, including the lining, shall be of such consistency as to sustain themselves in order that the structure may be assembled.

The numeral 1 indicates a sheet of metal which forms the outer wall of the front, bot-

tom, and back of the box. This sheet is bent to the proper form, as shown in Fig. 1 of the drawings. Separate pieces are united to this sheet, forming the outer end walls. The outer end walls are joined to the sheet forming the outer wall of the sides and bottom, as by angle-irons 3, rivets being employed for this purpose. Angle-irons 4 may also be placed on the corners at the bottom to support the structure at this point and also to afford a finish. Strips 5 may also be placed around the top of the sides and end to form a support and also a finish for this part of the box. A lining 6 is then placed within the structure, this lining being composed of a fireproof material formed in sheets of a size equal at least to the dimensions of the sides, bottom, and ends of the box. In the construction of these devices it has been found that asbestos-board, which is comparatively stiff, meets the requirements. These sheets are placed in proper position in the box, and the inner wall 7 is then placed in position. This wall may consist of a single piece of sheet metal forming the inner wall of the front, back, and bottom of the box; and the asbestos lining which has been placed in position and of the required thickness will form a proper support for this inner wall. The inner walls 8 of the ends are formed of sheets of metal, as in the case of the outer wall. A filling piece or finish 9 is then placed between the sheets forming the outer and inner walls of the box, if desired, in this instance the sheets of asbestos forming the sides and ends terminating at such distance below the top edge of the box as to allow the insertion of these filling-pieces. The rivets for securing the filling-pieces 5 to the front wall may pass entirely through the box, if desired, as shown in Fig. 1, thus holding the filling-pieces in place and also firmly uniting the outer and inner walls of the box.

The rivets uniting the angle-irons to the bottom and end corners may, if desired, pass through both the outer and inner walls of the box or only through the angle-iron and that wall to which it is secured. A groove 10 may be formed in the filling-piece 9, if desired, for the reception of a packing or the like to be hereinafter described.

The cover is united with the box in the usual manner, as by means of hinges, and is constructed of sheet metal with a lining of asbestos-board, as above described. In the 5 form of cover shown two sheets 11 and 12 are preferably used, forming the outer and inner walls, respectively. These are united as by means of rivets passing through the angle-irons 13, which latter serve as a finish for the 10 box and also extend below the inner surface of the cover and form a flange surrounding the upper edge of the box.

A packing 14 is located in the groove 10 in the filling-piece 9. This packing is constructed of a fireproof material, as asbestos, and in the preferred form of the invention, as shown in the drawings herein, is of tubular form, as clearly shown in Fig. 4 of the drawings. This packing is preferably secured in the groove 10, and the tubular form provides an air-space in the packing, as well as providing means whereby the joint between the upper edge of the box and the cover is completely packed against the passage of 25 heat.

In Fig. 3 of the drawings I have shown a modified form of the invention in which an inner metallic plate 15 is inserted, the space between this inner plate and the outer plates 30 being occupied by asbestos cloth or the like. The packing in the form of invention shown in this figure consists of a sheet of asbestos cloth doubled back upon itself in such manner as to form a loop or tube 16 at the inner edge, against which the cover may press when 35 it is closed to securely pack the joint between the upper edge of the box and the cover. The body of this packing, formed of the two parts 17, which lie against each other, project downward into the box, being secured between the plates forming the same. As shown 40 in said Fig. 3, this packing is located between the outer plate 1 and the filling-piece 19, the rivets securing these parts together passing 45 through this packing.

It is obvious that the details of construction may be varied to a considerable extent without departing from the scope of the invention and that the precise form of the sheets 50 forming the sides and ends of the box as herein shown need not be adhered to, and the form of uniting the several pieces and location of the rivets for accomplishing this need not be strictly followed, as these forms may 55 be departed from to a considerable extent within the skill of the ordinary mechanic.

What I claim as my invention, and desire to secure by Letters Patent, is—

1. A fireproof box having its inner and outer 60 walls each formed as to two sides and the bottom of a continuous strip of metal, and the end walls of each composed of plates secured to the continuous sides and bottom, with a space on all sides between the inner and outer walls, a fireproof filling interposed between the inner 65

and outer walls, angle-irons embracing each end and bottom corner of the box, said angle-irons extending beyond the plane of the inner surface of the box and having bolts passing through one face of the angle-iron, through 70 the interior filling into the box, and a cover composed of inner and outer plates with a fireproof filling between said plates.

2. A fireproof box having its inner and outer 75 walls each formed as to the bottom and two sides of a continuous strip of metal, and the ends formed of plates secured to the continuous sides and bottoms, a fireproof filling located on all sides between the inner and outer walls, angle-irons bounding each end and bottom corner of the box, a filling-piece located between the inner and outer walls of the box at the upper edge thereof, and a cover composed of two plates of metal with a fireproof 80 filling located between the said plates.

3. A fireproof box having its inner and outer walls each formed as to two sides and bottom of a continuous strip of sheet metal, and the ends formed of two plates secured thereto, a fireproof packing located on all sides between the 90 inner and outer walls, angle-irons bounding the end and bottom corners of the box with one arm of the angle-iron extending beyond the plane of the face of the inner wall of the box, bolts extending through said arm and through 95 the fireproof packing into the box, a filling-piece located between the inner and outer plates and extending around the upper edge of the box, and a cover formed of two plates of metal with a fireproof filling between said 100 plates.

4. A fireproof box having its outer and inner walls formed of metal, said outer walls being formed as to three sides by a continuous strip of sheet metal forming two sides and the bottom of the box, end walls of plate form registering with said continuous sides and bottom, angle-irons for retaining said parts in place, the inner walls of the box being formed as to three sides from a continuous strip of metal 105 bent to form and with plate-like end walls, a fireproof filling interposed between the outer and inner walls, and a cover formed of a pair of plates inclosing a fireproof material and secured by an angle-iron said angle-iron having 110 one of its sides resting upon the face of a plate with the other part of the angle-iron extending across the plates and intermediate filling, and forming a flange projecting below the upper edge of the sides and ends of the 115 box.

5. A fireproof box having its outer and inner walls formed of sheet metal, a single continuous sheet of metal forming three of the outer walls, and a single continuous sheet of metal forming three of the inner walls, end walls of plate form coöperating with said continuous strips of metal and means for securing them thereto, a fireproofing material arranged intermediate the inner and outer walls of the 120 125 130

box, a filling-piece arranged about the upper edge of the box, a cover for the box and a packing located at the upper edge of the box adapted to be engaged by the under surface

5 of the cover.

6. A fireproof box containing outer and inner walls of metal, said outer and inner walls being formed as to three sides from continuous strips of metal bent to form, plate-like

10 end walls, and means for securing them in place with relation to the first-named walls, insulating material arranged intermediate the inner and outer walls of the structure, a filling-piece arranged adjacent to the upper edge

15 of the walls, and a web of insulating material folded upon itself and arranged between the filling-piece and the outer walls of the structure, said web of insulating material extending above the walls and forming a compressible loop, and a cover adapted to compress the extending portion of the web of insulating material.

7. A fireproof box having inner and outer walls formed of metal with a fireproof filling 25 interposed between said inner and outer walls, angle-irons embracing the corners of the box, said angle-irons extending beyond the plane of the inner surface of the box and having a fastening passing through one face of the angle-iron and through the interior filling into the box, and a cover composed of inner and outer plates with a fireproof filling between said plates.

8. A fireproof box having inner and outer 35 walls formed of metal with a fireproof filling interposed between the outer and inner walls, and a cover formed of a pair of plates inclosing a fireproof material and secured by an angle-iron, said angle-iron having one of its sides

40 resting upon the face of a plate, with the other

part of the angle-iron extending across the plates and intermediate filling and forming a flange extending below the upper edge of the sides and ends of the box.

9. A fireproof box having its outer and inner walls formed of metal with a fireproof filling interposed between said outer and inner walls, angle-irons embracing the corners of the box, said angle-irons extending beyond the plane of the inner surface of the box and having fastenings passing through one face of the angle-iron through the interior filling into the box, and a cover formed of a pair of plates inclosing a fireproof material and secured by an angle-iron, said angle-iron having one of its 45 sides resting upon the face of a plate, with the other part of the angle-iron extending across the plates and intermediate filling and forming a flange projecting below the upper edge of the sides and ends of the box. 50

10. A fireproof box having an outer wall formed of metal and an inner wall formed as to two sides and the bottom of a continuous strip of metal and the remaining sides of the inner wall composed of plates secured to the 55 continuous sides and bottom with a space on all sides between the inner and outer walls, a fireproof filling interposed between the inner and outer walls, angle-irons embracing the corners of the box, said irons extending beyond 60 the plane of the inner surface of the box and having fastenings passing through one face of the angle-iron through the interior filling into the box, and a cover composed of inner and outer plates with a fireproof filling between 70 said plates. 75
